(57) CLAIM

The ornamental design for a merchandising system, as shown and described.

DESCRIPTION

FIG. 1 is a front perspective view of a merchandising system.

FIG. 2 is a front perspective view of the merchandising system.

FIG. 3 is a top plan view of the merchandising system.

FIG. 4 is a bottom plan view of the merchandising system.

FIG. 5 is a rear elevation view of the merchandising system.

FIG. 6 is a front elevation view of the merchandising system.

FIG. 7 is a right side elevation view of the merchandising system shown in FIG. 1.

FIG. 8 is a left side elevation view of the merchandising system shown in FIG. 1.

FIG. 9 is a front perspective view of the merchandising system, showing additional units in broken lines.

FIG. 10 is a front perspective view of the merchandising system shown in FIG. 9.

FIG. 11 is a front perspective view of the merchandising system shown in FIG. 9; and,

FIG. 12 is a front perspective view of the merchandising system shown in FIG. 11.

The broken line disclosure shown in FIGS. 9-12 is for illustrative purposes only and forms no part of the claimed design.
